ARCH SUPPORT

Helen E. Reineke, Faribault, Minn.

Application December 19, 1936, Serial No. 116,812

4 Claims. (Cl. 36—71)

This invention relates to an arch support for a foot.

The invention has for its object to provide in a manner as hereinafter set forth, a support of the class referred to which when used possesses a massaging characteristic; strengthens the arch muscles of the foot due to its massaging characteristic; stimulates circulation which helps to feed and build stronger muscles; gives the necessary support in cases of weak foot muscles and fallen arches; is easy and comfortable to wear; eliminates congestion of blood flow in the foot and is capable of being built to properly fit an individual case of foot ailment.

Further objects of the invention are to provide in a manner as hereinafter set forth, an arch support for the purpose referred to which is simple in its construction and arrangement, strong, durable, resilient, thoroughly efficient when used, readily assembled and comparatively inexpensive to manufacture.

With the foregoing and other objects which may hereinafter appear, the invention consists of the novel construction, combination and arrangement of parts as will be more specifically described and are as illustrated in the accompanying drawing wherein is shown an embodiment of the invention, but it is to be understood that changes, variations and modifications may be resorted to which fall within the scope of the invention as claimed.

In the drawing:

Figure 1 is a longitudinal sectional view of the arch support as applied to the simulation of the foot, the latter being shown in side elevation,

Figure 2 is a top plan view of the arch support partly broken away,

Figure 3 is an inverted plan of the arch support partly broken away,

Figure 4 is a view looking towards the inner side edge of the arch support,

Figure 5 is a section on line 5—5, Figure 2,

Figure 6 is a view on line 6—6, Figure 2, on reduced scale,

Figure 7 is an inverted plan view of the upper section of the arch support and further illustrates the intermediate section of the arch support applied to the lower face of the upper section,

Figure 8 is a top plan view of the bottom section of the arch support, and

Figure 9 is a top plan view of the form of insertable lift employed.

The arch support includes a top, an intermediate and a bottom section generally indicated at 1, 2 and 3 respectively. The sections 1 and 3

are preferably formed from kid leather. The section 2 consists of sponge rubber. The section 1 consists of a body part 4 and a foldable flap 5 extending from the inner edge of body part 4 intermediate the ends of the latter. Body part 4 of section 1 has its edges conforming in contour to the edges of section 3. The latter includes a straight outer edge 6 slightly inclined outwardly from front to rear, a rounded rear edge 7, an inner side edge 8 of ogee curvature and a curved forward edge 9. The edge 9 is of greater length than the edge 7. The forward portion of section 3 is of greater width than the rear portion.

The section 2 has its edges conforming in contour to the edges of sections 1 and 3 but the length and width of section 2 is slightly less than the length and width of either section 1 or 3. The section 2 has its edges positioned inwardly adjacent to the edges of the sections 1 and 3, whereby sections 1 and 3 are formed with marginal portions 10, 11 respectively, arranged outwardly adjacent the edges of the section 2. The latter is formed of a rear portion 12, a front portion 13, and an intermediate portion having a reduced part 14 and an enlarged part 15 which is of segmental contour in longitudinal section and substantially of segmental contour in transverse section. The part 15 in top plan is substantially semi-oval in contour. The part 14 borders the outer side edges of the sections 1 and 3. The part 15 merges into the inner side of the part 14, into the forward end of the portion 12 and rear end of the portion 13. The part 14 merges into the portions 12 and 13. The part 15 is formed with a circular row of spaced upstanding ports 16.

The flap 5 is bent inwardly to oppose the bottom of the part 15 and is interposed between said part 15 and section 3. The flap 5 is of substantially oval-shaped contour and is formed with a row of openings 17 which align with the inner ends of the ports 16. The section 1 is formed with a series of openings 18 which align with the outer ends of the ports 16.

The marginal portions 10 and 11 of the sections 1 and 2 are secured together by a row of stitching 19. Sections 1 and 3 and flap 5 are secured together by a row of stitching 20. The row of stitching 19 has its ends terminate in proximity to the ends of the row of stitching 20 whereby a portion of the section 3 is free of connection to the flap and section 1 and such portion, indicated at 21, coacts with the flap 5 to provide a pocket 22 opening at the inner side of the arch support and arranged at the bottom of the latter.

The flap 5 in connection with the portion 23 of the section 1 forms a chamber 24 for the enlarged part 15 of the section 2. The bend 25 of the flap 5 provides the intermediate portion of the side edge of the section 1.

The pocket 22 is employed for inserting lifts 26 of the form shown in Figure 9 for fitting purposes.

The part 15 of the section 2 provides the metatarsal support and functions not only longitudinally but transversely in such connection.

The portions 12, 13 and 14 of the section 2 preferably will be one-eighth of an inch in height whereby the part 15 of section 2 will have its height as desired.

15 The ports 16 and openings 17, 18 provide for the needed ventilation. The section 2 provides for the massaging function when the arch support is used.

With reference to Figure 1 the simulation of a 20 foot is indicated at 27 and which is applied there-to the arch support in accordance with this invention and is indicated generally at 28.

What I claim is:

1. An arch support comprising top, bottom and 25 intermediate sections, said top and bottom sections being formed of bendable material, said intermediate section being formed of resilient material, said intermediate section intermediate its ends having a portion of greater thickness than its remaining portion, the said remaining portion of said intermediate section being interposed between said other sections, said top section being formed with a bendable flap extending inwardly to oppose the bottom of said portion of greater thickness whereby the latter is spaced from the bottom section, means for securing said inturned flap to the top and bottom sections whereby a portion of the bottom section is freed from said intermediate section and provides in connection 40 with the flap a pocket for inserts, and means for securing the top and bottom sections together adjacent the edges of the said remaining portion of the intermediate section.

2. An arch support comprising top, bottom and 45 intermediate sections, said top and bottom sections being formed of bendable material, said intermediate section being formed of resilient material, said intermediate section intermediate its ends having a portion of greater thickness than its remaining portion, the said remaining portion of said intermediate section being interposed between said other sections, said top section being formed with a bendable flap extending inwardly to oppose the bottom of said portion of greater thickness whereby the latter is spaced from the bottom section, means for securing said inturned flap to the top and bottom sections whereby a por-

tion of the bottom section is freed from said intermediate section and provides in connection with the flap a pocket for inserts, and means for securing the top and bottom sections together adjacent the edges of the said remaining portions of the intermediate section, said portion of greater thickness being provided with ports, and said top section and said flap being formed with openings registering with said ports.

3. An arch support comprising bendable top 10 and bottom sections and a resilient intermediate section, said intermediate section being enlarged intermediate its ends, said enlargement disposed lengthwise and transversely with respect to the top and bottom sections and terminating at one 15 end adjacent the outer side edges of said sections and having its other end substantially flush with the inner side edges of the top and bottom sections, said enlargement being of segmental contour in longitudinal section and sloping from one 20 end towards its other, said top section being formed at its inner side with an integral flap positioned against the lower face of said enlargement, means for securing said flap to the said section, said means being so disposed relative to said sections to provide a part of the bottom section free 25 of connection to the other sections and with said part coacting with said flap to provide a pocket, and means for securing said top and bottom sections together outwardly adjacent the edge of 30 the intermediate section.

4. An arch support comprising bendable top and bottom sections and a resilient intermediate section, said intermediate section being enlarged intermediate its ends, said enlargement disposed 35 lengthwise and transversely with respect to the top and bottom sections and terminating at one end adjacent the outer side edges of said sections and having its other end substantially flush with the inner side edges of the top and bottom 40 sections, said enlargement being of segmental contour in longitudinal section and sloping from one end towards its other, said top section being formed at its inner side with an integral flap positioned against the lower face of said enlargement, means for securing said flap to the said 45 sections, said means being so disposed relative to said sections to provide a part of the bottom section free of connection to the other sections and with said part coacting with said flap to provide 50 a pocket, and means for securing said top and bottom sections together outwardly adjacent the edge of the intermediate section, said enlargement being formed with a series of ports, and said top and flap having openings registering with said 55 ports.
